UNITED STATES PATENT OFFICE

152,283

DESIGN FOR A PAPER PUNCH

William H. Misson, Los Altos, Calif.

Application January 13, 1947, Serial No. 136,115

Term of patent 14 years

(Cl. D74—1)

To all whom it may concern:

Be it known that I, William H. Misson, a citizen of the United States of America, residing in the city of Los Altos, county of Santa Clara, State of California, have invented a new, original, and ornamental Design for a Paper Punch, of which the following is a specification, reference being had to the accompanying drawing, forming part thereof.

Figure 1 is a perspective view of the paper punch showing my new design;

Figure 2 is a front end view;

Figure 3 is a side elevation; and

Figure 4 is a plan view.

I claim:

The ornamental design for a paper punch, as shown.

WILLIAM H. MISSON.
